United States Patent Office

Des. 191,192
Patented Aug. 29, 1961

191,192

ADVERTISING DISPLAY SIGN

Nick J. Schwab, Orchard Park, and Charles A. Oddo,
Buffalo, N.Y., assignors to International Breweries,
Inc., Detroit, Mich., a corporation of Michigan

Filed Oct. 19, 1959, Ser. No. 57,967

Term of patent 14 years

(Cl. D1—12)

FIG. 1

FIG. 3

FIG. 1 is a perspective view showing the rear, top, and one end of an advertising display sign embodying our new design;

FIG. 2 is a front elevational view thereof on a larger scale; and

FIG. 3 is an elevational view of the opposite end of FIG. 1 on a larger scale.

The broken-line representations in FIGURE 2 are for the purposes of illustration only.

We claim:

The ornamental design for an advertising display sign, as shown and described.
